UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,842, dated May 23, 1899.

Application filed April 28, 1899. Serial No. 714,598. Term of patent 14 years.

To all whom it may concern:

Be it known that I, BENJAMIN F. MAYO, a citizen of the United States, residing at Salem, in the county of Essex and Commonwealth of Massachusetts, have invented and produced a new and original Design for a Protective Slug, of which the following is a specification.

Figure 1 is an end view of a protective slug, illustrating my design; and Fig. 2 shows the same in elevation viewing it from its open end.

The leading feature of my design for a protective slug consists of an elongated body bent transversely at two points to present wings united by a connecting portion, the said wings and connecting portion each being concaved.

The protective slug comprises an elongated

body bent transversely at two points, as at *a*, to present a rather sharp corner and leave wings *b b'* and a connecting portion *c*, said connecting portion and wings being each concaved from their outer faces inwardly.

Having fully described my design, what I claim, and desire to secure by Letters Patent, is—

The design for a protective slug substantially as herein shown and described.

In testimony whereof I have signed my name to this specification in the presence of two subscribing witnesses.

BENJAMIN F. MAYO.

Witnesses:

GEO. W. GREGORY,
MABEL PARTELOW.
